(57) **CLAIM**

We claim the ornamental design for a OTF knife, as shown and described.

DESCRIPTION

FIG. 1 is a perspective view of a OTF knife, showing our new design;

FIG. 2 is a right side view thereof;

FIG. 3 is a left side view thereof;

FIG. 4 is a top view thereof;

FIG. 5 is a bottom view thereof;

FIG. 6 is a front view thereof; and,

FIG. 7 is a back view thereof.

The dot-dot-dash broken lines represent an unclaimed boundary of the claimed design. The remainder of the broken lines depict portions of the OTF knife in which the design is embodied that form no part of the claimed design.
